TREATMENT OF HYDROCARBON OILS

John Warren McCaffrey, Chicago, Ill., assignor,
by means assignments, to Universal Oil Products Company, Chicago, Ill., a corporation of Delaware

Application January 6, 1932, Serial No. 584,927
Renewed February 13, 1937

5 Claims. (Cl. 196—62)

This invention relates to the treatment of hydrocarbon oils and more particularly refers to a process and apparatus for the maximum production of hydrocarbon oils boiling within the motor fuel range and possessing relatively high antiknock properties and other qualities of refinement.

More particularly this invention contemplates the cracking of a crude, topped crude or other type of heavy charging stock for the production of a cracked end point distillate within the motor fuel boiling range and a flashed residuum. The residuum is treated in a conjointly operated system with nascent hydrogen in presence of fixed gases, produced in the different stages of the complete process, under highly super-atmospheric pressure for the production of an hydrogenated end point distillate within the motor fuel boiling range. The process essentially includes the commingling of these cracked and hydrogenated gasoline products and their re-conversion in a third system under independently controlled conditions for the formation of a reformed gasoline of high antiknock value and other desirable qualities.

A feature of the invention is the utilization of the noncondensable gases produced in the different stages of the complete process as a source of supply of hydrogen. Although in the molecular state the appreciable amount of hydrogen produced in the process assists the hydrogenating reactions which of course are promoted and primarily influenced by the active or nascent hydrogen introduced to the process under elevated temperatures and pressures. The presence of the excess supply of hydrogen influences the hydrogenating reaction similarly as excess of any reagent influences a chemical reaction from equilibrium towards completion in any indicated direction. Illustration of the advantage of this feature of recycling gases to the hydrogenating operation will appear later in this application.

In a more specific embodiment, the invention contemplates subjecting raw oil charging stock to conversion conditions in a coil and chamber, withdrawing all of the conversion products out of the bottom of the chamber and discharging them under substantially reduced pressure into a vaporizer, fractionating, condensing and collecting the desirable portion of the vapors while returning the insufficiently converted products separated out in the fractionator to the cracking coil for further conversion, withdrawing the flashed distilled residual oils from the vaporizer and subjecting them, in the presence of nascent hydro-

gen, to elevated temperatures and highly super-atmospheric pressure in an hydrogenation zone, fractionating, condensing and collecting the resulting vapors under greatly reduced pressure, while returning the insufficiently converted products separated out in the fractionator to the hydrogenating coil for further conversion, commingling the cracked and hydrogenated distillates and subjecting a selected mixture to independently controlled conversion conditions in a third system, fractionating, condensing and collecting the desirable vapors while returning reflux condensate from the fractionator to either the cracking zone or the hydrogenating zone, or dividing it between the two zones and utilizing a selected portion of the fixed gases produced in the three steps of the operation as a supply of hydrogen-containing gases to assist the work of the nascent hydrogen introduced to the hydrogenation zone.

In another embodiment residual oils from any cracking process whether employing the feature of withdrawing all reaction products out of the bottom of the reaction chamber and discharging the same to a zone of reduced pressure, or so treating only the non-vaporized oils from the reaction chamber, or producing residuum without any pressure reduction thereon, may be subjected to treatment with nascent hydrogen in any conjointly operated hydrogenating process, and the cracked and hydrogenated distillates obtained from the conjointly operated processes reformed in a third system as described in the previous embodiment. Thus the quality and quantity of the residuum subjected to hydrogenation is in a degree controllable and by that very fact the relative quality and quantities of the cracked and hydrogenated distillates are controllable within limitations.

In still another embodiment the cracked and hydrogenated distillates may be blended in any desirable proportions in order to obtain useful and valuable blends of gasoline without subjecting the mixture to the reforming step described in this process. Thus the hydrogenated distillate, generally of higher quality than the cracked distillate produced in the conjointly operated system, may be blended with the cracked distillate much the same as cracked and straight run gasolines are blended together in order to improve the motor fuel qualities of the straight run gasoline. Similarly this blending of hydrogenated and cracked gasolines will improve the motor fuel qualities of the cracked gasoline, in any cases to such a degree that the blended product will have

many preferred uses as a motor fuel, even approaching in some cases the quality of some of our present day premium motor fuels.

A more complete and detailed knowledge of 5 the operation of the various steps in the process covered by this invention can be had from a description of the preferred operation of the process in connection with the accompanying drawing.

10 Raw oil charging stock is introduced to the system through valve 1 and line 2 and directed by means of pump 3 through line 4 and valve 5 to the upper section of fractionator 6, wherein it comes into direct contact with the hot vapors 15 therein, and assists in their fractionation, while being itself preheated and stripped of any light low boiling fractions. The non-vaporized raw oil, together with reflux condensate from the fractionator, is withdrawn through line 7 and valve 16 20 and directed by means of pump 9 through valve 10 and line 11 to the first heating coil 12 suitably disposed within any type of appropriate furnace A. If preferred, any portion or all of the raw oil charging stock may be pumped directly 25 through line 13 and valve 14 and line 11 to heating coil 12. The charged materials are subjected to conversion conditions and discharged from the furnace through line 15 and valve 16 into chamber 17, wherein sufficient time element 30 is afforded for the completion of conversion reactions. All of the conversion products are withdrawn from the bottom of the chamber through line 18 and discharged under reduced pressure through pressure reducing valve 19 into vaporizer 35 20, wherein the separation of the liquid and vaporous products occurs.

The vaporous products pass through line 21 and valve 22 into the lower section of fractionator 6, wherein they are fractionated by means 40 of direct contact with that portion of the raw oil charging stock delivered overhead and any other refluxing material introduced to the fractionator. The fractionated vapors pass overhead through line 23 and valve 24 and are cooled 45 and condensed in coil 25 located in suitable condenser box, and pass through valve 26 and line 27 to be collected in receiver 28, wherein the liquefied and gaseous products are separated. Any required portion of the distillate may be withdrawn 50 from receiver 28 through line 29 and valve 30 and directed by means of pump 31 through line 32 and valve 33 to the top of fractionator 6 as refluxing material. The insufficiently converted intermediate products separated out in the 55 fractionator, together with any unvaporized portion of the raw oil introduced thereto, are directed to the cracking coil, as previously described.

The residual oils resulting from the flash distillation are withdrawn from the vaporizer through line 34 and valve 35 directed by means 60 of pump 36 through line 37 and valve 38 and line 39 to the heating coil 40 disposed within any suitable type of furnace B. Nascent hydrogen 65 may be introduced to the system through line 108, valve 107, and lines 104 and 39 to the heating coil 40, where the charged materials are subjected to elevated temperatures and highly super-atmospheric pressures. The products from the 70 coil are discharged through line 41 and valve 42 into reaction chamber 43, wherein the hydrogenation reactions initiated in the coil are completed, and the vaporous and non-vaporous products separated. The liquid products or 75 sludge accumulating in the reaction chamber may

be withdrawn through line 44 and valve 45 as the operation progresses or, if the operation is continued until coke or a substantially dry carbonaceous material is formed in the bottom of reaction chamber, the same may be removed at 5 the end of the operation through manhole 46.

Vaporous products from the reaction chamber are directed to the lower section of fractionator 49 through line 47 and pressure reducing valve 48. In reducing the pressure from the highly 10 super-atmospheric order maintained on the hydrogenating coil and chamber to that maintained on the succeeding units of the hydrogenating system, a series of automatic pressure-reducing valves may be used in line 47, although only valve 15 48 is shown on the drawing. The vaporous products are fractionated with the assistance of refluxing material introduced into the top of the fractionator and pass overhead through line 50 and valve 51 and are cooled and condensed in coil 20 52 located in suitable condenser box, and pass through line 53 and valve 54 to be collected in receiver 55, wherein the gaseous and liquefied products are separated. Any required portion of the distillate from receiver 55 may be withdrawn 25 through line 56 and valve 57 and directed by means of pump 58 through line 59 and valve 60 to the top of fractionator 49 as refluxing material. The insufficiently converted intermediate compounds separated out in the fractionator 30 are withdrawn from the fractionator through line 61 and valve 62 and directed by means of pump 63 through line 39 and valve 64 to heating coil 40.

Any portion of the cracked distillate collected 25 in receiver 28, which is not used as refluxing material in fractionator 6, may be withdrawn through line 65 and valve 66 to be commingled with any portion of the hydrogenated distillate 40 collected in receiver 55 which is not used as refluxing material in fractionator 49, and which is withdrawn from receiver 55 through line 68 and valve 67. The commingled distillates are directed by means of pump 69 to the heating coil 70, disposed within any suitable type of furnace C, 45 wherein the charged materials are subjected to independently controlled conversion conditions of temperature and pressure. The products from coil 70 are discharged through valve 71 and line 71' into the lower section of fractionator 72, 50 wherein the vapors are fractionated with the aid of refluxing material introduced at the top of this zone. The fractionated vapors pass overhead through line 73 and valve 74 and are cooled and condensed in coil 75 located in suitable condenser box and pass through valve 76 and line 77 55 to be collected in receiver 78, wherein the liquefied and gaseous products are separated. Any required portion of the distillate collected in receiver 78 may be withdrawn through line 79 and valve 80 and directed by means of pump 81 through line 82 and valve 83 to the top of fractionator 72 as refluxing material. Reflux condensate from the fractionator is withdrawn through line 84 and valve 85 and directed by 60 means of pump 86 through line 87 either through valve 90 and line 11 to the heating coil 12, or through lines 87 and 88, valve 89 and line 39 to heating coil 40, or partly to both. The reformed gasoline collected in receiver 78 may be withdrawn to storage or use through line 102 and valve 103.

When desired any portion of the cracked distillate collected in receiver 28 may be blended with any portion of the hydrogenated distillate 75

collected in receiver 55 and the mixture of the two distillates withdrawn from the system (means not shown on the drawing) without subjecting the blended product to the reforming 5 step of the process, thus avoiding the reforming step of a mixture of cracked and hydrogenated gasolines would be desirable when the mixture as withdrawn from the conjointly operated cracking and hydrogenating systems is of such quality 10 to render it useful and valuable as such for motor fuel purposes.

Non-condensable products separated out and collected in receiver 28 are withdrawn through valve 93 and line 94 and commingled with non- 15 condensable products separated out and collected in receiver 55, which are withdrawn therefrom through valve 97 and line 98 and also with non-condensable gases separated out and collected in receiver 18, which are withdrawn therefrom 20 through valve 101 and line 104. This mixture of hydrogen-containing gases produced in the various steps of the process is directed by means of pump 105 through valve 106 and lines 104 and 39 to the heating coil 40 to increase the supply 25 of hydrogen-containing gases and to assist the nascent hydrogen in conversion of the flashed residual oil charged to the hydrogenating system. Means are provided for the release of excess pressure on the various systems by withdrawal of 30 excess gases collected in receivers 28, 55 and 18 through pressure control valves 110, 112 and 114, respectively, in lines 109, 111 and 113, respectively.

Conversion temperatures employed in the 35 cracking operation may range from 800 to 950° F., more or less. Pressures employed in the cracking zone may vary from atmospheric to super-atmospheric as high as 500 pounds, or more, per square inch. Pressures maintained on the vaporizer are 40 substantially less than those employed in the cracking zone and may range from atmospheric to 100 pounds, or more, per square inch. Equalized or differential pressures may be employed on the succeeding units of the cracking system.

45 Conversion temperatures employed in the hydrogenating operation may range from 600 to 900° F., more or less. Pressures employed in the hydrogenating zone may vary from substantially atmospheric to highly super-atmospheric of 50 the order of 5000 pounds, or more, per square inch. Reduction from this high pressure to a much lower pressure before admitting the hydrogenated vapors to succeeding units of the system may be 55 accomplished by one or more pressure reducing valves. Equalized or differential pressures may be employed on the remaining elements of the hydrogenating system.

Conversion temperatures employed in the third 60 heating coil may range from 900 to 1050° F., more or less, while the pressures may range from atmospheric to super-atmospheric as high as 500 pounds, or more, per square inch.

As a specific example of the results accomplished by the process covered by this invention, 65 a Mid-Continent crude oil of about 29° A. P. I. gravity was subjected to conversion conditions of approximately 900° F. and 200 pounds pressure. This cracking operation resulted in the formation of 70 percent of gasoline within the motor fuel boiling range of approximately 58° A. P. I. gravity and 20 percent of flash residuum of approximately 15° A. P. I. gravity. The gasoline product possessed relatively poor antiknock qualities, which may be in part attributed to the fact that the 75 crude oil contained 15 per cent of straight-run

gasoline with an average gravity of 52° A. P. I. The anti-knock rating of the blended cracked and straight-run gasoline was equivalent approximately to a blend of 64 per cent iso-octane and 36 per cent of normal heptane or a benzol equivalent 8 of 50 per cent. The residual oil from the cracking operation, subjected to a temperature of 850° F. in the second heating coil in the presence of a sufficient supply of nascent hydrogen and non-condensable gases produced in the various steps 10 of the process, and under pressure of 2000 pounds per square inch, yielded a product also having a low anti-knock quality. The reconversion of the flashed residuum from the cracking operation resulted in the formation of 18 per cent of gasoline, 15 based on the crude oil, within the motor fuel boiling range, having an anti-knock rating approximately equivalent to that of a blend of 76 per cent of iso-octane and 24 per cent normal heptane, or an approximate benzol equivalency of 62 20 per cent. All of the cracked distillate was mixed with all of the hydrogenated distillate and subjected in the reforming step of the process to a temperature of 930° F. and 500 pounds pressure, which operation resulted in the formation of a reformed gasoline of considerably improved anti-knock quality, gum content and stability. The reformed gasoline had an anti-knock rating approximately equivalent to that of a blend of 84 25 per cent of iso-octane and 16 per cent normal heptane or a benzol equivalency of 70 per cent.

Analysis of the non-condensable gases from the cracking operation revealed the presence of 9% 30 of hydrogen with the usual other gaseous compounds of carbon and hydrogen, such as methane, 35 ethane, etc. The non-condensable gases from the hydrogenating operation showed approximately 25% of hydrogen, which might be expected from the fact that the hydrogenating reaction takes place in the presence of excess amount of hydrogen. The re-forming operation of the process resulted in the production of a gas containing approximately 3% hydrogen. This amount of hydrogen produced in the three steps of the process, 40 although in the molecular state, is a valuable adjunct in assisting the hydrogenating reaction and assuring a maximum saturation with hydrogen. This feature becomes apparent to one skilled in the art or with the point of view of the physical chemist from a consideration of mass reactions. 45

A proof of the value to the process of this feature of recirculating the non-condensable gases produced in the cracking, hydrogenating and reforming operations for use in assisting the hydrogenating operation was had, when, during the operation of the process, all the non-condensable 50 gases produced were liberated from the system excepting an amount necessary to maintain desirable pressures. As a result of this change in operation it was found that the yield of gasoline resulting from the hydrogenating of the flashed residuum was decreased to 15% based on the crude oil charged to the process, and that the same product showed a lower antiknock rating, 55 approximately 69 octane number or a benzol equivalency of 55. Furthermore, it was found that this gasoline contained more gum-forming and sulfur compounds, which could easily be inferred from the fact that hydrogen, which has a pronounced de-gumming and de-sulfurizing influence, was not in such copious supply as in the preferred operation of the process. The increase 60 in the amount of gum-forming constituents averaged 100 mgs. The product had a very slight odor of mercaptans, whereas under the preferred 65

operation of the process the hydrogenated gasoline product has no "sour" odor.

Naturally enough the reformed gasoline obtained from mixing and recracking this hydrogenated gasoline of inferior quality with the cracked gasoline would suffer an appreciable, though not necessarily corresponding, decrease in anti-knock properties and increase in gum and sulfur contents. This increase in the amount of gum-forming and sulfur constituents and decrease in anti-knock value when the non-condensable gases of the process were not being used to assist the hydrogenating operation is evidence of the beneficial effect of the utilizing of such an amount of molecular hydrogen available under the preferred operating conditions of the process.

The relatively low anti-knock rating of the cracked gasoline produced in the first stage of this process rendered that product by itself of little value as a motor fuel in the present market of premium gasolines. On the other hand the anti-knock rating of the hydrogenated gasoline approximately equivalent to that of ethyl standard gave that gasoline a qualified value among the premium motor fuels of the day. However, it was found that by proportioning the amounts of cracked gasoline and hydrogenated gasoline to form a uniform mixture which was not subjected to the reforming step of the process, a product was obtained that had considerably improved anti-knock properties over the cracked gasoline and was generally useable as a motor fuel. As a specific example of the improvements in anti-knock rating that may be obtained by blending alone, without employing the reforming step of the process, it was found that a blend of equal proportions of the cracked gasoline in the example previously specified having an anti-knock rating of 64% iso-octane and the hydrogenated gasoline of the same example having an anti-knock rating of 76% iso-octane had an anti-knock rating approximately equal to that of a blend of 72% iso-octane and 28% normal heptane or a benzol equivalency of approximately 58% benzol. Thus by blending the cracked and hydrogenated gasolines without resorting to the reforming step of the process larger quantities of a valuable commercial grade of motor fuel may be economically obtained.

I claim as my invention:

1. In processes for cracking hydrocarbon oil of the character in which the oil is subjected to cracking conditions of temperature and pressure, thence separated into vapors and residue in a separating zone, the vapors subjected to fractionation to condense intermediate products heavier than gasoline and the lighter vapors finally condensed to form gasoline-containing distillate, the improvement which comprises subjecting the gasoline-containing distillate to temperature conditions adequate to reform and improve the antiknock characteristics of the gasoline components thereof, recovering the reformed distillate and gases resulting from the reforming operation and subjecting such gases and the residue of the cracking process to hydrogenating

conditions of temperature and pressure in an independent hydrogenating zone and recovering distillate from the hydrogenation of the residue and combining the same with the distillate from the cracking operation to be concurrently reformed therewith. 5

2. A hydrocarbon oil conversion process which comprises subjecting the oil to cracking conditions of temperature and pressure in a cracking zone and separating the same into vapors and residue, dephlegmating the vapors to condense fractions thereof heavier than gasoline, finally condensing the dephlegmated vapors and separating the resultant gasoline distillate from the incondensable gases, passing such gases and said residue to a hydrogenating zone maintained under hydrogenating conditions of temperature and pressure and hydrogenating the residue therein, separating a gasoline-containing distillate from the thus treated residue and combining portions thereof with portions of the first-mentioned distillate, passing the resultant mixture through an independent heating zone and heating the same therein sufficiently to substantially increase the anti-knock properties of the gasoline content of the mixture, recovering the gasoline thus retreated, and supplying incondensable gases formed by the last-named heating step to the hydrogenating zone. 15 20 25

3. A conversion process which comprises subjecting hydrocarbon oil to cracking temperature under pressure and separating the same into vapors and residue, fractionating the vapors and separating therefrom a light fraction containing low anti-knock gasoline hydrocarbons, subjecting said residue to hydrogenation to produce lower boiling products therefrom, combining lower boiling products thus formed with said light fraction, subjecting the resultant mixture to cracking conditions adequate to enhance the anti-knock value of its gasoline content, separating resultant anti-knock gasoline from incondensable gases and supplying at least a portion of the latter to the hydrogenating step to furnish hydrogen for the hydrogenation of said residue. 30 35 40 45

4. A conversion process which comprises subjecting heavy hydrocarbon oil to relatively mild cracking, thereby forming unvaporized residue and gasoline fractions of low anti-knock value, reforming said gasoline fractions to enhance their anti-knock value, by a dehydrogenating conversion treatment at higher temperature than that at which said heavy oil is cracked, thereby liberating hydrogen from the gasoline fractions, combining resultant hydrogen-containing gas 50 55 from the reforming operation with unvaporized residue from said relatively mild cracking and subjecting the combined materials, independently of said heavy oil, to hydrogenating conditions adequate to produce lower boiling products from 60 the residue.

5. The process as defined in claim 4 further characterized in that low anti-knock gasoline fractions produced by the hydrogenating operation are reformed together with said gasoline 65 fractions of the relatively mild cracking.

J. WARREN McCAFFREY.
